The patent or application file contains at least one drawing executed in color. Copies of this patent or patent application

publication with color drawing(s) will be provided by the U.S. Patent and Trademark Office upon request and payment of the necessary fee. Further, high-quality electronic copies of the drawings are available in the Office's electronic record of this application.

FIG. 1 is a front elevational view of a controller for medical equipment showing our new design;

FIG. 2 is a back elevational view thereof;

FIG. 3 is a top plan view thereof;

FIG. 4 is a bottom plan view thereof;

FIG. 5 is a side elevational view of the right side thereof; FIG. 6 is a side elevational view of the left side thereof; and FIG. 7 is a perspective view taken generally from the top, front, left-hand side thereof.

FIG. 8 is a front elevational view of a controller for medical equipment showing an embodiment of our new design;

FIG. 9 is a back elevational view thereof;

FIG. 10 is a top plan view thereof;

FIG. 11 is a bottom plan view thereof;

FIG. 12 is a side elevational view of the right side thereof;

FIG. 13 is a side elevational view of the left side thereof; and FIG. 14 is a perspective view taken generally from the top, front, left-hand side thereof.

FIG. 15 is a front elevational view of a controller for medical equipment showing an embodiment of our new design;

FIG. 16 is a back elevational view thereof;

FIG. 17 is a top plan view thereof;

FIG. 18 is a bottom plan view thereof;

FIG. 19 is a side elevational view of the right side thereof; FIG. 20 is a side elevational view of the left side thereof; and FIG. 21 is a perspective view taken generally from the top, front, left-hand side thereof.

FIG. 22 is a front elevational view of a controller for medical equipment showing an embodiment of our new design;

FIG. 23 is a back elevational view thereof;

FIG. 24 is a top plan view thereof;

FIG. 25 is a bottom plan view thereof;

FIG. 26 is a side elevational view of the right side thereof; FIG. 27 is a side elevational view of the left side thereof; and FIG. 28 is a perspective view taken generally from the top, front, left-hand side thereof.

FIG. 29 is a front elevational view of a controller for medical equipment showing an embodiment of our new design;

FIG. 30 is a back elevational view thereof;
FIG. 31 is a top plan view thereof;
FIG. 32 is a bottom plan view thereof;
FIG. 33 is a side elevational view of the right side thereof;
FIG. 34 is a side elevational view of the left side thereof; and
FIG. 35 is a perspective view taken generally from the top, front, left-hand side thereof.
FIG. 36 is a front elevational view of a controller for medical equipment showing an embodiment of our new design;
FIG. 37 is a back elevational view thereof;
FIG. 38 is a top plan view thereof;
FIG. 39 is a bottom plan view thereof;
FIG. 40 is a side elevational view of the right side thereof;
FIG. 41 is a side elevational view of the left side thereof; and
FIG. 42 is a perspective view taken generally from the top, front, left-hand side thereof.
FIG. 43 is a front elevational view of a controller for medical equipment showing an embodiment of our new design;
FIG. 44 is a back elevational view thereof;
FIG. 45 is a top plan view thereof;
FIG. 46 is a bottom plan view thereof;
FIG. 47 is a side elevational view of the right side thereof;
FIG. 48 is a side elevational view of the left side thereof; and
FIG. 49 is a perspective view taken generally from the top, front, left-hand side thereof.
FIG. 50 is a front elevational view of a controller for medical equipment showing an embodiment of our new design;
FIG. 51 is a back elevational view thereof;
FIG. 52 is a top plan view thereof;
FIG. 53 is a bottom plan view thereof;

FIG. 54 is a side elevational view of the right side thereof;
FIG. 55 is a side elevational view of the left side thereof; and,
FIG. 56 is a perspective view taken generally from the top, front, left-hand side thereof.
The broken lines in the figures represent portions of the controller for medical equipment that form no part of the claimed design.
